UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE REPEATER CIRCUITS.

Application filed January 4, 1918, Serial No. 210,263. Renewed April 28, 1923.

To all whom it may concern:

Be it known that I, EDGAR D. JOHNSON, a citizen of the United States, residing at East Orange, in the county of Essex, State of New Jersey, have invented certain new and useful Improvements in Telephone Repeater Circuits, of which the following is a full, clear, concise, and exact description.

Early in the development of telephone apparatus, it was recognized as desirable to increase the distance that signals could be transmitted, and a repeating device was used for this purpose. A repeater is essentially a unilateral conductor, however, whereas it is necessary to provide for the two-way transmission of signals. This leads to the use of first, repeaters permanently connected in the telephone line and prevented from singing by means of balancing networks, or, second, repeaters which are connected to the telephone line in one manner for transmission in one direction and connected in another manner for transmission in the other direction.

This invention relates to expedients of the latter type, wherein the switching of the repeater is automatically effected in response to current such as voice current impressed on the telephone line.

The invention provides a single repeating device which is normally connected between the two terminals of the telephone line for transmission in one direction, a reversing switch being provided between each telephone line and the repeater. A voice relay is connected in shunt to each of the telephone lines and the operation of either of the voice relays serves to render the other inoperative and changes the connections of the repeater to the line terminals, in case it is necessary that such change be made, for transmission of current in the proper direction. Upon the cessation of voice current in the telephone line the repeater remains normally connected to transmit current in one direction through the telephone lines.

For further details of the invention reference is made to the drawing, in which the signal figure shows diagrammatically a two-way repeating circuit embodying the invention.

In the drawing the telephone lines 1 and 2 terminate in the electromagnetic switches 3 and 4 respectively, which are adapted to

properly connect the telephone lines to the repeater 5. This repeater is here shown as of the mechanical type, but any other type of repeater may be employed. The input leads 6 and 7 of the repeater are connected to the lines 8 and 9 respectively. The lines 8 and 9 terminate in the contacts 10 and 11 of the switch 3, the circuit through these contacts being completed as shown by means of the armatures 12 and 13. The input side of the repeater 5 is thus connected to the line 1 through the contacts 10 and 11 and their associated armatures. The output side of the repeater, by means of the leads 16 and 17, is connected to the contacts 18 and 19 which are in contact with their respective armatures 20 and 21 as shown. The armatures 12, 13, 20 and 21 are normally in their outermost positions as shown. The armatures 20 and 21 are permanently connected to the telephone line 2.

In the position of switches 3 and 4, shown, the repeater 5 is adapted to receive current coming into the line 1 and to repeat this current with amplified energy to the line 2. In order to transmit current from the line 2 to the line 1, however, it is necessary to effect the operation of switches 3 and 4 to their alternate positions and this is done automatically by means which will now be described.

In shunt to the telephone line 1 is an alternating current relay or a voice relay 22, which is responsive to alternating or pulsating current, such as voice current, to cause the vibration of its normally closed contacts 23 and 24. The invention is not limited to any particular form of voice relay and as indicating one type of relay that may be employed, reference is made to the patent to Brown 1,185,472, telephony, May 30, 1916. The contact 24 is grounded, as shown, and the contact 23 is connected by way of lead 25 through one solenoid 26 of a polarized relay or master switch 27. A circuit is provided from the solenoid 26 through the battery 28 to ground, as shown. The voice relay 29, similar to 22, is connected in shunt to the line 2 and is provided with the vibrating contacts 30 and 31 which are connected in series with the solenoid 32 of the polarized relay, the latter solenoid being also supplied with current from the battery 28 by connections as shown.

The solenoids 33 and 34 of the electro-

- magnetic switches 3 and 4 are adapted to be connected by way of the leads 35 and 36 respectively through the armature 37 of the relay 27, and battery 28 to ground.
- 5 When the armature 37 of the polarized relay 27 is thus in its alternate position the battery 28 energizes the solenoids 33 and 34, thereby attracting armatures 12, 13, 20 and 21, which connects the input side of the repeater 10 5 to the line 2, and the output side of the repeater 5 to the line 1. This makes possible the transmission of current from the line 2 through the repeater 5 to the line 1. The operation of the polarized relay 27 is automatically effected in response to voice currents in the following way: voice currents coming in over the line 2 energize the voice relay 29, the contacts 30 and 31 of which are vibrated, thereby increasing the resistance 15 in the circuit in which they are included, this circuit comprising the solenoid 32 of the polarized relay 27 and the battery 28. This increase in resistance of the circuit including solenoid 32 sufficiently reduces the current 20 through the same, so that the magnetic field produced by the other solenoid 26 is effective to throw the armature 37 to its alternate position, in which position it effects the operation of the switches 3 and 4 as desired.
- 25 The operation of the voice relay 29, by means of the vibration of its contacts, also increases the resistance in a circuit including the solenoid of a relay 38, the armature 39 of which is connected in series with the solenoid of the voice relay 22. When the current through the relay 38 is thus decreased, the armature 39 assumes its open position, thereby opening the circuit to the voice relay 22 and rendering the same inoperative.
- 30 The voice relay 22 is consequently maintained inoperative by the voice relay 29 as long as the current is coming in over the line 2.

If, with the switches in the position shown 45 in the drawing, current were to come in over the line 1, the voice relay 22 would operate to decrease the current through the solenoid 26 of relay 27, but this would not effect the operation of the armature 37 and the switches 3 and 4 would maintain the positions shown. The operation of the voice relay 22 would also increase the resistance in the circuit of the relay 41, thereby releasing the armature 42, and opening up the circuit 50 of the voice relay 29 which is consequently rendered inoperative.

When current is no longer coming in over either of the lines 1 or 2, the armatures 39 and 42 are attracted to their closed positions due 60 to the increase in current through their corresponding solenoids, the vibrating contacts being quiescent, whereby the voice relays 22 and 29 are both connected in shunt to their respective lines. The master switch 65 or polarized relay 27 remains in the position

which it last assumed and in that position the circuit is effective to transmit current in one direction. When it is necessary to reverse the connection of the repeater for transmission in the opposite direction, the reversal is automatically effected by means of the voice relays.

It is obvious that the invention and its various features may be embodied in circuits other than the circuit here shown by way of example.

What is claimed is:

1. The combination of two telephone lines terminating in armatures, electromagnetic means for controlling said armatures, vibratile contact relays for controlling said means, a repeater between said lines, means whereby said relays control said repeater, and means whereby one of said relays controls the operation of another of said relays, said repeater being connected to transmit current in only one direction between said lines in the absence of current to be repeated.

2. A repeating system comprising two telephone lines terminating in armatures, electromagnetic means for controlling said armatures, vibratile contact relays for controlling said means, a repeater comprising an input circuit and an output circuit adapted to be connected between said lines and controlled by said relays, each relay being responsive to current in its corresponding line to render the other relay inoperative, and said armatures connecting said input circuit to one of said lines and connecting said output circuit across said other line to condition the system for transmission in one direction over said lines in the absence of current to be repeated.

3. A signaling system comprising two lines, a vibratile contact A. C. relay in shunt to each of said lines, a repeater for said lines and normally adapted to repeat from one of said lines to the other, means whereby said relays control the connection of said repeater to said lines, said means comprising a vibratile contact for said relays, a solenoid and an armature controlled thereby, a source of current in circuit with said contact and solenoid, the vibration of said contact serving to effectively deenergize said solenoid during said vibration, and means whereby one of said A. C. relays controls the operation of another relay, said last mentioned means comprising a relay having a movable contact in circuit with said other relay.

4. A signaling system comprising two lines, a repeater therefor and normally connected for transmission in one direction thebetween, a switch between each line and said repeater whereby the two-way transmission of signals is possible, said switches having independently movable contacts, a voice relay for each of said lines, and con-

nections whereby each of said relays is adapted to operate both of said switches and to render the other relay inoperative.

5. In a telephone repeater system, a switch comprising a pair of windings, an armature controlled thereby, a source of current for said windings, two sets of vibrating contacts, each set being in circuit with said source and with one of said windings, and 10 an electromagnet controlling each of said contacts.

6. The combination of two telephone lines, a relay for each of said lines, mechanically independent armatures for said relays, a 15 repeater for transmitting current in both directions between said lines, means whereby said relays control said repeater, and means whereby one of said relays controls the operation of the other relay, said repeater being connected to transmit current in only one direction between said lines in the absence of current to be repeated.

7. The combination of two telephone lines, a relay for each of said lines, a unilateral 25 repeater for transmitting current in both directions between said lines, means whereby said relays control said repeater, and means whereby one of said relays controls the operation of the other relay, said last 30 mentioned means comprising an armature for one of said relays, a solenoid controlled thereby, and an armature for said solenoid in circuit with another of said relays.

8. The combination of two telephone lines, 35 a relay for each of said lines, a repeater between said lines, means whereby said relays control said repeater, and means whereby one of said relays controls the operation of the other relay, each of said relays comprising a vibrating contact, an auxiliary relay having a solenoid and a movable contact, said solenoid and a source of current being in circuit with said vibrating contact, the vibration of said contact serving 40 to change the resistance in circuit with said auxiliary relay and operate said contact to affect the operation of another of said first mentioned relays.

9. The combination of two telephone lines, 50 a relay for each of said lines, a repeater between said lines and normally connected for repeating in one direction therebetween, means whereby said relays control said repeater, and means whereby one of said relays controls the operation of the other relay.

10. The combination of two telephone lines, a relay for each of said lines, said relays having mechanically independent armatures, a repeater between said lines and 60 normally connected for repeating in one direction therebetween, means whereby said relays control said repeater, and means whereby one of said relays controls the operation of the other relay.

11. The combination of two telephone

lines, a relay associated with each of said lines, a repeater adapted to be connected between said lines and controlled by said relays, said repeater being normally connected for transmission in one direction between said lines, each relay being responsive to current in its corresponding line to render the other relay inoperative.

12. A signaling system comprising two lines, a repeater therefor and normally connected for transmission in one direction therebetween, a switch between each line and said repeater whereby the two-way transmission of signals is possible, a voice relay for each of said lines, each of said relays 75 being adapted to operate both of said switches and to render the other relay inoperative.

13. A signaling system comprising two lines, a repeater therefor and normally connected for transmission in one direction therebetween, a switch between each line and said repeater whereby the two-way transmission of current is possible, a 80 vibratile A. C. relay for each of said lines, and connections whereby each relay operates one of said switches and renders the other relay inoperative.

14. A repeating system comprising two telephone lines terminating in armature, electromagnetic means for controlling said armatures, vibratile contact relays for controlling said means, and a repeater adapted to be connected between said lines and controlled by said relays, each relay being responsive to current in its corresponding line to render the other relay inoperative and said repeater being effectively connected to efficiently transmit current in one direction between said lines in the absence of current 100 to be repeated.

15. The combination of two telephone lines terminating in armatures, electromagnetic means for controlling said armatures, vibratile contact relays for controlling said means, a repeater adapted to be connected between said lines, means whereby said relays control said repeater, and means whereby one of said relays controls the operativeness of the other relay, one side of one of 115 said lines being connected to an output terminal of said repeater in the absence of current to be repeated, and one of said armatures connecting the other side of said one line to another output terminal of said repeater in the absence of current to be repeated.

16. A repeating system comprising two telephone lines terminating in armatures, electromagnetic means for controlling said armatures, vibratile contact relays for controlling said means, and a repeater adapted to be connected between said lines and controlled by said relays, each relay being responsive to current in its corresponding 120 125 130

line to render the other relay inoperative, one side of one of said lines being connected to an output terminal of said repeater in the absence of current to be repeated, and 5 one of said armatures connecting the other side of said one line to another output terminal of said repeater in the absence of current to be repeated.

17. A line, a unidirectional repeater 10 adapted to be reversibly connected therein, a shunt circuit deriving current from said line, and connected to said line in the absence of current to be repeated, said circuit including a vibratile contact voice relay responsive to voice currents to effectively 15 open its contacts throughout the duration of said voice currents, a movable contact for opening and closing said circuit, and means responsive to current impressed on said line 20 for controlling said contact.

18. The combination of two lines, a unidirectional repeater adapted to be reversibly connected therebetween, said repeater having output terminals normally connected to one of said lines and input 25 terminals normally disconnected from said line, a voice relay deriving current from said one line for controlling the connection of said repeater to said lines, and means comprising a movable armature for rendering said relay unresponsive to current approaching said repeater over the other of said lines while permitting said relay to respond to current approaching the repeater 30 over said one line. 35

In witness whereof, I hereunto subscribe my name this 29th day of December A. D. 1917.

EDGAR D. JOHNSON.
